Attorney, Agent, or Firm—Bacon & Thomas, PLLC

[57] CLAIM

The ornamental design for a protective helmet, as shown and described.

DESCRIPTION

FIG. 1 is an upper left frontal perspective view of a protective helmet showing our new design; and,

FIG. 2 is an upper right rear perspective view thereof.

The surfaces or portions of the protective helmet not shown in the drawings or described in the specification form no part of the claimed design.

1 Claim, 2 Drawing Sheets

FIG. 1

FIG. 2
